DRIVING MECHANISM

Raymond A. Walter, New York, N. Y., Bertha Baer Walter, executrix of said Raymond A. Walter, deceased, assignor to Goodman Manufacturing Company, Chicago, Ill., a corporation of Illinois

Application May 6, 1931, Serial No. 535,522
Renewed October 3, 1934

6 Claims. (Cl. 74—40)

This invention relates in general to devices for imparting reciprocating motion, and more particularly has reference to a driving mechanism for shaker conveyors.

5 In driving reciprocating conveyors, it is desirable for the efficient operation of the same, to impart a forward stroke gradually accelerated for substantially two-thirds its length, and rapidly decelerated for the remainder of its length; 10 and a back stroke correspondingly, but reversely, rapidly accelerated for substantially one-third its length and gradually decelerated for the remainder of the stroke. This theory of the operation of reciprocating conveyors is fully set forth in my

15 Patent No. 1,804,577.

My present invention comprehends a mechanism adapted to impart reciprocating motion of this character for driving shaker conveyors. The mechanism which I provide in performing this 20 operation is of simpler construction than has heretofore been achieved for imparting such motion, and in addition possesses certain inherent advantages to be hereinafter more fully described, not present in similar devices heretofore 25 provided.

An object of this invention is to provide a driving mechanism for a reciprocating conveyor of simple construction.

Another object of this invention is to provide 30 a driving mechanism for a reciprocating conveyor comprising a rotating crank arm, a rocking lever and a driving lever joined by connecting rods in such relation as to produce accelerated and retarded backward and forward strokes of reciprocating motion for driving a shaker conveyor.

Still another object of this invention is to provide 35 a driving mechanism for a reciprocating conveyor comprising a rotating crank arm, a rocking lever, and a driving lever joined in such a relation as to produce accelerated and retarded forward and backward strokes of reciprocating motion; in which the rocking lever is formed in a 40 novel manner to provide for the accomplishment of forward and backward strokes of reciprocating motion imparted by the driving lever, in exactly the same time interval.

A further object of this invention is to provide 45 a driving mechanism for a reciprocating conveyor, constructed to allow the transfer of conveyor stresses and strains directly on the bottom of a frame enclosing the same, permitting a housing therefor to be constructed of lighter material than has heretofore been susceptible of use.

A still further object of this invention is to provide a driving mechanism for a reciprocating conveyor having a driving lever projecting through a housing therefor with provision for sealing the housing against the entrance of foreign material.

5 A still further object of this invention is to provide a driving mechanism comprising a rocking lever, a driving lever, connecting arms and pins for pivoting the driving levers to the connecting 10 arms, and for fulcruming the driving and rocking levers to a housing, in which the pins are held in place by the side walls of the housing for enclosing the mechanism.

With these and other objects in view, which 15 may be incident to my improvements, the invention consists in the parts and combination to be hereinafter set forth and claimed, with the understanding that the several necessary elements comprising my invention may be varied in construction, proportions and arrangement without departing from the spirit and scope of the appended claims.

In order to make my invention more clearly understood, I have shown in the accompanying 25 drawing, means for carrying the same into practical effect without limiting the improvements in their useful applications to the particular constructions which, for the purpose of explanation, have been made the subject of illustration. 30

In the drawing forming a part of this invention:

Figure 1 is a top view of the mechanism with the cover for the housing removed.

Figure 2 is a top view of the driving lever, 35 showing the aperture in the housing cover for admitting the same, in plan.

Figure 3 is a side view of the mechanism showing the housing and pins connecting the element, 40 in plan.

Figure 4 is a diagrammatic view showing a graph of the motion imparted by the mechanism.

Figures 5, 6, and 7 are diagrammatic views of the operative elements of the mechanism, showing the relative positions of the same during the 45 operation thereof to impart accelerated and retarded forward and backward strokes of reciprocating motion.

Figure 8 is a diagrammatic view of the operative elements of the mechanism, similar to Figure 50 7, except that a less efficient type of rocking arm is substituted for that shown in Figure 7 for the purpose of illustrating the advantages resulting in the use of my novel rocking lever.

Referring more particularly by numerals to 55

the drawing and more especially to Figure 1, it will be seen that my mechanism comprises a housing 1, formed with integral longitudinally extending partitions 2 and 3. The housing is further formed with integral flanges 4 along the side edges adjacent the bottom. Flanged members 5 and 6 are mounted across the bottom of the housing at the ends, extending over on each side thereof. The members 5 and 6 are adapted 10 to act as flexible bed plates for mounting of the housing on the floor of a working, through extension members fitting in depressions 7 provided therein, between the top surfaces of the flanged members and the roof of a working in 15 the manner shown in my Patent No. 1,804,578.

One side wall of the housing is formed with a split bearing for receiving a drive shaft 8, coupled to any suitable prime mover, such as an electric motor capable of imparting motion 20 thereto at a comparatively high speed. A small pinion 9 is keyed on the end of the shaft 8 within the casing, fitting between the wall of the casing and the longitudinal partition 2. The pinion 9 is adapted to mesh with a pinion 11 25 also mounted between the wall of the casing and the longitudinal partition 2, carried on a shaft 12 journaled in aligned bearing boxes 13 and 14 fitted in slots provided in the longitudinal partitions 2 and 3 of the housing. A small pinion 15 is keyed on the shaft 12 intermediate 30 the bearing boxes 13 and 14.

The pinion 15 is adapted to mesh with a pinion 16 also mounted between the longitudinal partitions 2 and 3, carried on a shaft 17. The 35 ends of the shaft 17 are journaled in aligned bearing boxes 18 and 19, also fitted in slots provided in the partitions 2 and 3, like the bearing boxes 13 and 14.

The gear train formed by the pinions 9, 11, 15 40 and 16, are adapted to reduce the speed of rotation of the shaft 8 to practical limits for transfer to a crank arm 21, fixed on the end of the shaft 17. The crank arm 21 is adapted to be connected to the tops of rocking levers 22 and 23 45 through a connecting rod 24. The connecting rod 24 is pivoted on a wrist pin 25, carried on the crank arm, and a pin 26 extending between the tops of the rocking levers, respectively. It is to be particularly noted that the rocking levers 50 22 and 23 are angularly formed.

The bottoms of the rocking levers are pivoted on a pin 27, journaled in aligned bearings provided in the wall of the housing and the longitudinal partition 3 formed therein.

55 The rocking levers 22 and 23 are adapted to be connected to a driving lever 28 through arms 29 and 31, pivoted on a pin 32 carried between the rocking levers 22 and 23 and a pin 33 fixed on the driving lever. The driving lever 28 is pivoted on a pin 30, having the ends anchored in one wall of the casing and the partition 29 therein, adjacent the bottom, in the same plane with the pin 27 fulcruming the rocking levers. Strains 60 on the mechanism are thus directed to the bottom of the housing and taken up by the flexible bed plates 5 and 6.

The driving lever 28 is formed with an extension 34, provided with an aperture 35 for connection to a reciprocating conveyor unit to drive 70 the same. The top of the driving lever is cylindrically formed and provided with a face piece 36. A cover 37, as shown in Figure 2 is adapted to be fitted on the top of the housing containing the foregoing interconnected elements. The 75 cover is formed to accommodate portions of the

elements projecting above the rim of the housing and with a longitudinal aperture 38 to admit the extension 34. The portion of the housing cover 37 adjacent the face piece 36 is correspondingly formed to permit the extension 34 on the driving lever 28 to reciprocate in the slot 38. The face piece 36 prevents the entrance of foreign material into the housing through the slot 38. 5

It will be seen from the foregoing that the rotary motion imparted by the shaft 8 is adapted 10 to be reduced through the gears 9, 11, 15 and 16 and translated into a reciprocating motion by operation of the rocking levers 22 and 23 through connection of the wrist pin 25 on the crank arm by the connecting or crank rod 24. The levers 15 22 and 23 rock back and forth by connection to the crank arm operating on the fulcrum journal or pin 27, anchored between one wall of the casing and the partition 3 adjacent the bottoms thereof. 20

This motion is unsuitable for shaker conveyor operation, however, and is changed to an accelerated and retarded reciprocation by my novel changing means, comprising the connecting rods 29 and 31 and the driving lever 28, the latter 25 rotating on the fulcrum journal or pin 30 in the same plane with the pin 27 fulcruming the rocking levers, adjacent the bottom of the housing 1. The driving lever 28 is adapted to impart a desirable accelerated and retarded reciprocating motion by reason of the angular relation of the pins 32 and 33 on the rocking levers and the driving lever, respectively, on which the connecting rods 29 and 31 are pivoted with respect to the pins 27 and 30, fulcruming the rocking 30 levers and the driving lever. 35

The motion imparted by the driving lever 28 is shown in graph on the diagram in Figure 4, 40 indicating the relative velocities which may be attained at all points of a complete forward and backward stroke of the lever. All of the figures in the drawing show the mechanism in position for transporting material on a shaker conveyor to the right. 45

The figures in degrees on the graph in Figure 4 45 indicate the elapsed portion of the return stroke or rotation, 360° constituting a complete rotation or return stroke. The distance of the curve above or below the center lines 41 and 42 represent velocity per second in any convenient unit 50 of measurement.

The forward stroke as indicated by the line 43 begins at 41 and ends at 52, where the back stroke is begun, ending at 41 where the successive forward stroke begins. 55

It will be noted that the initial forward velocity begins at zero and gradually accelerates to 60 reach its maximum beyond the two thirds point of the forward stroke, or 120° of a complete return stroke. The velocity is then rapidly retarded reaching zero at 180° and equally rapidly accelerated in a reverse direction to reach its peak near the 240° point, then gradually retarded to the end of the backward stroke. The reciprocating motion imparted by the driving lever 28 65 thus gradually accelerates for substantially two thirds the length of the forward stroke and rearwardly decelerates for the remainder of the stroke and rapidly accelerates for substantially one third of the backward stroke and gradually decelerates for the remainder of the stroke. There is thus achieved corresponding but reverse backward and forward strokes of accelerated and retarded reciprocating motion, de- 70 75

sirable for the efficient operation of a shaker conveyor.

It will be noted that this motion varies decidedly from the curve which would be generated by a simple crank motion.

In Figure 5 is shown in solid skeletal lines the position of the motion changing means at the end of a forward or the beginning of a backward stroke. When the crank 21 is rotated through any short specified partial revolution or time interval 44, the motion changing means assumes a new position, as shown by the dotted lines. The travel of the conveyor connected to the drive is indicated by the numeral 45.

In Figure 6 is shown in solid skeletal lines the position of the motion changing means at the end of the backward stroke. The partial revolution, or time interval, 46 is of exactly the same length as 44 in Figure 5. The dotted lines show the position of the various parts at just the same time interval before the end of the stroke, as the interval after the beginning of the back stroke indicated by the dotted lines in Figure 5. It is to be particularly noted, however, that the travel of the conveyor as indicated by the numeral 47, is much smaller. In a like manner, the motion changing means distorts the entire cycle of the regular crank motion to a series of velocities, as shown in graph in Figure 4.

In Figure 7 there is shown the position of the various parts of the motion changing means at both ends of the stroke, one end being shown in solid lines, the position for the other end being shown in dotted lines. It will be seen that a straight line drawn through the two positions of the wrist pin 25 exactly subtends the two positions of the pin 26 on the rocking lever. This demonstrates that both forward and backward strokes are each made in 180° in the revolution of the crank 25, or in exactly the same time interval.

The angular formation of the rocking levers 22 and 23 will be appreciated in connection with this description of operation. In Figure 8 is shown a straight rocking lever 48. In the use of straight rocking levers, the pins 27, 32 and 26 are on a straight line. A straight line cannot be extended through both positions of the pin 26, however. As a result, one stroke of the drive is necessarily made in less than 180° of the revolution of the crank 21. Accordingly, one stroke is made in less than the other, and the action of the conveyor is consequently jerky or bumpy, and not smooth and uniform as is obtained by the type of drive shown in Figure 7, in which the rocking levers 22 and 23 are angularly formed.

I attain the results enumerated by placing the pin 26, as shown in Figure 7, at an angle with respect to the pins 27 and 32, and secure the acceleration and retardation of conveyor motion as shown in the velocity curve in Figure 4. This is accomplished, as has been previously described, by arranging the various motion changing parts so that the angular relations between the pins 27, 32, 33 and 30, shall at both ends of the strokes be approximately as shown by the solid skeletal lines in Figures 5 and 6. Attention is to be directed to the fact that in each instance the lever with the more acute angle on lines 27, 32, 33 and 30, moves faster with relation to the other. As the rocking levers 22 and 23 must move at a fixed speed with relation to the crank 21, the driving lever 28 is subjected to a wide range in velocity, as illustrated in the velocity curve in Figure 4.

In the assembly of my drive, the rocking levers 22 and 23, the driving lever 28 and connecting

rods 29 and 31 are arranged so that the same may be loosely assembled outside of the housing 1 on the pins 32 and 33. In this loosely assembled condition, the levers and rods may be lowered into the compartment formed by one wall of the casing, and the integral partition 3, and the pins 27 and 30 for fulcruming the rocking levers and the drive lever, respectively, inserted.

The foregoing assembly of parts is adapted to fit so closely between the wall of the partition and the casing that there will be but slight play of the pins 32 and 33, and thus the necessity for fastening means for the pins is eliminated.

When it is required to disassemble the drive, it is merely necessary to remove the pins 27 and 30, when the entire assembly may be lifted out of the housing and allowed to fall apart.

There is accomplished by this invention a driving mechanism of simple construction comprising fulcrumed rocking and driving levers joined by a connecting rod in such relation as to produce accelerated and retarded backward and forward strokes of reciprocating motion of the most efficient character for operating a shaker conveyor, the mechanism being of a novel assembly where in the necessity of fastening devices for securing certain of the elements heretofore present in such structures, is eliminated.

While I have shown and described the preferred embodiment of my invention, I wish it to be understood that I do not confine myself to the precise details of construction herein set forth by way of illustration, as it is apparent that many changes and variations may be made therein, by those skilled in the art without departing from the spirit of the invention, or exceeding the scope of the appended claims.

I claim:

1. A driving mechanism for a reciprocating conveyor, comprising a housing, a crank arm operating therein, and a pair of interconnected levers connected to the crank arm for imparting accelerated and retarded strokes of reciprocating motion, said levers being fulcrumed adjacent the bottom of the housing.

2. A driving mechanism for a reciprocating conveyor, comprising a crank arm, a fulcrumed rocking lever, a driving lever fulcrumed on the same plane as the rocking lever, rods connecting the crank arm and levers together, the connection of the rod from the crank arm to the rocking lever being offset with respect to the fulcrum of the driving lever and the connection of the rod from the rocking lever to the driving lever.

3. A driving mechanism for a reciprocating conveyor, comprising a crank arm, a fulcrumed rocking lever, a fulcrumed driving lever, rods connecting the crank arm and levers together, the connection of the rod from the crank arm to the rocking lever being offset with respect to the fulcrum of the driving lever and the connection of the rod from the rocking lever to the driving lever, and intermediate said connections.

4. A driving mechanism for a reciprocating conveyor including a crank arm, a connecting rod connected thereto at one of its ends, a rocking lever connected to the opposite end of said connecting rod and driven therefrom, another connecting rod connected to said rocking lever at a point spaced from its point of connection to said first mentioned connecting rod, another rocking lever, a connection between said connecting rod and one lever arm of said rocking lever, another lever arm on said rocking lever, said other lever arm comprising a driving member for imparting

corresponding but reverse accelerated and retarded backward and forward strokes of reciprocating motion to a conveyor trough.

5. A driving mechanism for a reciprocating conveyor comprising a source of rotary motion, means for translating the rotary motion into reciprocating motion comprising a crank, a connecting rod, a rocking lever driven thereby, a connecting rod connected thereto intermediate the 10 ends of said rocking member and a fulcrumed member connected to and operated by said connecting rod for correspondingly but reversely accelerating and retarding the respective forward and backward strokes of reciprocating motion.

6. In a drive mechanism for reciprocating conveyors, a reciprocable driven member, means for reciprocating said driven member with corresponding but reverse accelerated and retarded backward and forward strokes of reciprocating motion comprising a crank, a rocking member driven thereby, another rocking member, a connecting rod connecting one lever arm of said second-mentioned rocking member with said first mentioned rocking member, and another lever arm of said second mentioned rocking member comprising said reciprocable driven member. 10

RAYMOND A. WALTER.
